(57) **CLAIM**

The ornamental design for an electric bicycle, as shown and described.

DESCRIPTION

FIG. 1 is a top, rear and right-side perspective view a bicycle component showing my new design;

FIG. 2 is a bottom, front and left-side perspective view thereof;

FIG. 3 is a bottom, front and right-side perspective view thereof;

FIG. 4 is a right-side elevation view thereof;

FIG. 5 is a left-side elevation view thereof;

FIG. 6 is a front elevation view thereof;

FIG. 7 is a rear elevation view thereof;

FIG. 8 is a top plan view thereof; and,

FIG. 9 is a bottom plan view thereof.
